FRANK B. COMSTOCK, OF KNAPP CREEK, NEW YORK.

SPACING JACK.

Application filed December 3, 1923. Serial No. 678,293.

To all whom it may concern:

Be it known that I, FRANK B. COMSTOCK, a citizen of the United States, residing at Knapp Creek, in the county of Cattaraugus and State of New York, have invented new and useful Improvements in Spacing Jacks, of which the following is a specification.

In pumping oil from wells, it frequently happens that a volume of gas finds its way 10 into the space between the piston and the standing valve, but that the pressure of this gas is not enough to pass through the valve in the piston, and consequently remains in the lower part of the cylinder, thereby destroying the vacuum which is necessary to 15 open the standing valve and allow oil to enter the cylinder. To remedy this condition, the operator must increase the length of the cable connecting the pump rod with 20 the motive power used to actuate the pump, in order to allow the piston to move downwardly in the pump cylinder, thereby compressing the gas until it opens the valve in the piston and escapes to the other side thereof. It is then necessary to return to 25 the motive power which is frequently a considerable distance away from the pump to take the slack out of the cable after the piston and pump rod have been properly adjusted with relation to the standing valve. 30 This requires considerable time and labor, and must be frequently done when it is necessary to raise or lower the piston with a view of properly spacing the same with relation to the standing valve, and for other reasons too numerous to enumerate.

It is therefore the purpose of this invention to provide what I term a spacing jack by means of which the pump rod can be 40 raised or lowered in a comparatively quick and easy manner, and with a minimum of effort, the jack being very simple in construction, so that it can be manufactured and sold at a nominal cost.

More specifically stated, the invention 45 contemplates the provision of a jack of the character mentioned, the jack being designed to be slipped over one end of the pump rod, and subsequently turned to either

elevate or lower the rod as the occasion may 50 require, thus making it possible to properly space the piston with relation to the standing valve in a convenient manner.

Other objects and advantages of the invention will be apparent, when the following detailed description is read in connection with the accompanying drawing, the invention residing in the construction, combination and arrangement of parts as claimed.

In the drawing forming part of this application, like numerals of reference indicate similar parts in the several views, and wherein:

Figure 1 is a view showing the manner of 65 using the spacing jack.

Figure 2 is a view of the jack removed from the pump rod.

Figure 3 is an end elevation.

Figure 4 is a longitudinal sectional view 70 through the jack.

Referring to the drawing in detail, 10 indicates a portion of the pump casing which projects above the ground or surface, while 11 represents the pump rod. This rod is provided with a clamp 12 which normally reposes upon the horizontal arm 13 forming part of a pump jack of well known construction. The arm 13 has one end bifurcated to straddle or receive the pump rod 11, while the other end of this rod is pivoted as shown upon the standard 14 which rises from the base 15 of the pump jack construction. Pivoted upon the base 15 as at 16 is a bell crank lever, one branch 17 of which is terminally connected with the cable 18 which leads from a suitable source of motive power utilized to operate the pump. The bell crank lever is rocked upon its pivot 16 to reciprocate the pump rod 11, through the instrumentality of the arm 13 which is connected with the other branch 19 of the bell crank lever by the connecting member 20. This is a well known form of pump jack, and does not 75 form any part of the present invention. It 80

is obvious that when the arm 13 is elevated, the pump rod is simultaneously raised, as the clamp 12 which is secured to the rod 11 85

reposes upon the arm 13, and when the arm 13 is lowered, the rod 11 gravitates to its lowermost position, constituting the down stroke of the pump. For the reasons hereinabove pointed out and various other reasons, it is sometimes necessary to raise the pump rod 11 with a view of spacing or adjusting the position on the lower end of the rod 11 with relation to the standing 10 valve of the pump, and in order to accomplish this result without the necessity of running back and forth to the pump and motive power therefor I have devised what I term a spacing jack, clearly shown in the 15 drawings.

This jack comprises a tubular casing 21 which can be constructed from any suitable material and also vary in size without departing from the spirit of the invention. 20 Fitted in the lower end of this casing is a thimble 22 provided with threaded openings adapted to register with openings formed in the lower portion of the casing 21 in order to allow the handle bars 23 to be associated with this end of the jack. These handle bars have their inner extremities tapered and threaded as at 24 so that they can be conveniently screwed into or out of the openings provided in the thimble 22. 25 This thimble can be provided with any number of these openings to accommodate the desired number of handles, although but two of these handles are shown. Fitted in the upper end of the casing 21 is a nut 25 of sleeve like formation, and threaded into this nut is a hollow screw 26. The screw is of a length to extend approximately throughout the entire length of the casing 21, and includes a non-threaded upper portion 27 which projects above the casing 21; this portion is provided with a plurality of tapered threaded openings 28 to accommodate handle bars 29, there being two of such bars illustrated in the drawing. Each of 40 these bars has one end tapered and threaded as at 30, so that the bar can be conveniently screwed into one of the openings when use of the jack is desired. The handle bars 29 project laterally from the screw 26 and are 45 arranged in parallelism with the handle bars 23 carried by the lower end of the casing 21. Swivelly mounted upon the upper end of this screw is a cap 31 which is provided with an opening similar to the openings 28 of the screw to accommodate the tapered threaded extremity 32 of a short handle bar 33. When the jack is used, it is arranged 50 upon the pump rod 11 as shown in Figure 1, the pump rod passing through the screw 26 and also through the opening 34 formed centrally in the swivelled cap 31. A clamp 55 of any suitable character is then arranged upon the pump rod as shown in Figure 1, wherein this clamp is indicated at 35 and 60 is disposed upon the swivelled cap 31. When 65

it is desired to raise or lower the pump rod 11 for the purpose of properly spacing or adjusting the piston on the lower end of the rod with relation to the standing valve of the pump, the clamp 12 is loosened to permit the rod to slide through the jack. However when the clamp 12 is loosened, the clamp 35 is of course tightened to the rod, and by turning the screw 26 by means of the handle bars 29, the pump rod is 70 raised or lowered depending upon the direction of rotation of the screw. During this operation, the handle bar 33 is taken hold of to maintain the cap 31 stationary, so that the rotation of the screw 26 will not 75 be transmitted to the cap, which would of course result in uncoupling the sections of the rod 11, after the latter are turned incident to the raising or lowering of said rod. It will be manifest from an inspection of 80 the drawing, that the jack in its entirety is very simple in construction, light in weight, so that it can be easily ported from one pump to another to make the necessary 85 adjustments above referred to, and that by 90 reason of its use, this adjustment of the piston with relation to the standing valve of any pump can be accomplished in comparatively quick order as compared with the usual method above utilized in performing 95 this duty. After the adjustment has been made, the clamp 12 is again tightened on the rod 11, and the clamp 35 together with a jack as a whole removed from the rod. 100 If desired use may be made of an additional clamp 36, which is adapted to be associated with the rod 11 at a proper point in its length to prevent the rod from falling wholly within the cylinder or casing 10, which 105 might occur should the cable 18 break during the operation of the pump, or should the clamp 12 work loose from the rod. It might here be stated, that the component parts of the jack may be constructed from any 110 suitable material, vary in size and configuration and that the threads on the screw 26 may be either right or left hand threads without departing from the spirit of the invention. If the screw is provided with a left hand 115 thread use of the cap 31 and the handle bar 33 may be dispensed with.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

An adjusting jack for use with a rod member, said jack comprising a casing, a sleeve fitted in the upper end of the casing and interiorly threaded, a hollow adjusting

screw threaded in said sleeve and of a length substantially equal to that of the casing, and projecting above the sleeve, handle bars projecting laterally from said screw 5 above the casing, handle bars projecting laterally from the casing adjacent the lower end thereof, a cap swivelly mounted on the upper end of said screw and having a central opening to receive said rod member when passed through the screw, and a clamp 10 adapted to engage said rod member and repose upon the cap.

In testimony whereof I affix my signature.

FRANK B. COMSTOCK.
